UNITED STATES PATENT OFFICE.

ROBERT CARL RAHM, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING-CARRIER DRIVE MECHANISM.

1,282,914.

Specification of Letters Patent. Patented Oct. 29, 1918.

Application filed March 28, 1918. Serial No. 225,329.

To all whom it may concern:

Be it known that I, ROBERT CARL RAHM, citizen of the United States, residing at Wyomissing, near Reading, in the county of Berks and State of Pennsylvania, have invented certain new and useful Improvements in Braiding-Carrier Drive Mechanism, of which the following is a specification.

My invention relates to braiding carrier drive mechanism comprising clutch engaged driving and driven members, as illustrated in my Patent No. 1,256,038 issued Feb. 12, 1918; and it consists in the improved construction hereinafter fully described in connection with the accompanying drawings and the novel features of which are defined in the subjoined claims.

The general purpose of the present invention is to provide a self-contained carrier drive mechanism applicable to the usual braiding machine without special provision therefor; and the main novel features consist first in providing upon the fixed carrier post a stop device adapted to retain the driven member against rotation when it is disengaged from the driving member, and second in providing axial clutch operating means in connection with said post, as fully set forth in the following description of the embodiment illustrated.

Figure 1 is a sectional elevation of a mechanism embodying my complete invention, shown in connection with the top and bottom plates of an ordinary braider; one of the duplicated clutch pins being removed, and a portion of the stop collar being broken away to more clearly show the construction.

Fig. 2 is a plan view of the same, with the carrier drive disk removed but indicated in dotted lines together with an adjacent portion of the top plate of the machine.

Figs. 3 and 4 are detail views of detached parts.

The drawing indicates the top plate 5 of a braiding machine formed as usual with intersecting race-circles in which carrier drive-disks 9 are rotated to operate engaging bobbin carriers; these drive disks being intermittently rotated as in lace making braiders, by providing for clutch-controlled engagement of independently rotatable driving and driven members 10 and 11 respectively on each race-circle post 15 rising from the bottom plate 6 of the machine.

In the illustrated embodiment of my com- 55 plete invention the race-circle post 15 carries the entire clutch-controlled carrier-drive mechanism, so as to enable its use in place of the ordinary braiding drive mechanism without special provision in the ma- 60chine for its attachment.

The post as shown, is formed hollow, and contains a central clutch-operating device 16, to which pattern-controlled vertical movement is imparted; such movement being effected through a bell-crank lever 17 pivotally attached to it below the plate-secured base of the post and arranged to fulcrum against a bracket fixed beneath the plate as indicated, in connection with an interior 70 spring 18. The top of the post is provided with a stop collar 19, fixed thereto by one or more screw key-pins 20 as shown, and provided with a clutch-engaging rim recess 21 hereafter referred to. The top of the 75 central clutch-operating member 16 is provided with a clutch-engaging flange 22, by means of which the clutch pin or pins 25 carried by the driven carrier-disk member 11 are moved longitudinally to engage or 80 disengage the tooth projections 26 on the constantly rotated driving member 10.

The driven member 11, which comprises as shown a depending hub portion fixed to the carrier drive disk 9 by screws at 27 and 85 bearing upon the driving member 10, carries the clutch pins 25 in vertical guide ways 30 as indicated; each of said clutch pins having a radial side slot 31 in which the circular flange 22 of the central clutch-operat- 90 ing device 16 is constantly engaged so as to cause vertical movement of the clutch pins with said operating device while permitting rotary movement of the driven member 95 9-11 with its contained clutch pins 25 on 95 the non-rotatable operating device 15. As shown the latter is held against rotation by engagement therewith of the extended key pins 20 which fix the stop collar 19 to the post.

When the slideable clutch pin or pins 25 are lowered to engage the driving member 10, it is required that the driven member 11 be free to rotate with said member 10 upon the fixed post 15 and its central clutch-operating device 16; but when said clutch pin is in disengaged raised position as indicated in Fig. 1 said driven member should be

positively retained against rotation. The stop collar 19 of the fixed post is provided to serve this purpose, and the clutch pin 25 of the driven member is arranged to co-
 5 operate therewith; said stop collar being provided as shown with the rim recess 21 in which a projection 35 of the clutch pin is normally engaged by the spring-pressed upward movement of the clutch-operating
 10 device 16, while each downward movement of the latter releases such engagement, and leaves the member 11 with its contained clutch pin free to rotate, a clearance slot 36 being provided in the clutch pin 25 for the post stop collar 19 so as to permit of it.

While my complete invention is adapted to provide a self-contained apparatus applicable to an ordinary braider without special provision for attaching any part of it, as previously stated, certain novel features thereof may be otherwise applied within the invention as defined in the claims, as is indicated for instance in the post-secured stop device construction set forth in my application Serial No. 226,330 of even date herewith.

What I claim is:

1. A self-contained clutch-controlled carrier drive mechanism for braiding machines, comprising a hollow race-circle post having a stop collar and a slideable clutch-operating device; a driving member and a driven carrier-disk member independently rotatable on said post, a longitudinally movable clutch device in said driven member operatively engaged by said slideable device and adapted to engage and disengage said stop collar, and means for operating said slideable device.
2. A braiding carrier drive mechanism comprising a race-circle post carrying independently rotatable driving and driven

members and a slideable clutch member rotative with one of said rotary members, and a stop device fixed to said post and adapted to be engaged and disengaged by reverse movements of said slideable clutch member.

3. A braiding carrier drive mechanism comprising a hollow race-circle post carrying independently rotatable driving and driven members and a slideable clutch member rotative with one of said rotary members, and a clutch-operating device axially slideable in said hollow post.

4. A braiding carrier drive mechanism comprising a hollow race-circle post carrying independently rotatable driving and driven members and a slideable clutch member rotative with one of said rotary members, a clutch-operating device fixedly attached to said post and adapted to be engaged and disengaged by reverse movements of said slideable clutch member.

5. A braiding carrier drive mechanism comprising a hollow race-circle post, independently rotatable driving and driven members thereon, a stop device fixed thereto, a clutch operating device axially slideable therein, and a clutch device carried by said driven member and engaged by said operating device, said slideable clutch device being adapted to engage and disengage said fixed stop device when in inoperative and operative positions respectively.

6. A braiding carrier drive mechanism comprising a hollow race-circle post having a stop flange, driving and driven members independently rotatable on said post, a slideable clutch pin carried by one of said members, and a clutch-operating device non-rotatably slideable in said hollow post; said slideable clutch pin being adapted to engage and disengage the fixed stop flange.

ROBERT CARL RAHM.
